MOUTHPIECE FOR BREATHING APPARATUS
Jacques Y. Cousteau, Paris, France, and Emile
Gagnan, Montreal, Quebec, Canada, assignors to
La Spirotechnique
Filed Oct. 28, 1960, Ser. No. 65,729
Claims priority, application France Nov. 30, 1959
4 Claims. (Cl. 128—147)

The present invention relates to an improvement to the mouthpieces used in breathing apparatuses, particularly in underwater breathing apparatuses.

It is known that such mouthpieces are usually connected on the one hand to the diver's mouth through a short lateral conduit and on the other hand to a demand air regulator through an inhalation hose and to an expiration valve to ambient environment through an expiration hose, each one of said hoses being connected to one end of the mouthpiece.

During the operation of the breathing apparatus provided with such mouthpiece, when the carrier of the apparatus inhalates, the demand regulator admits to the inhalation hose an air flow which is to undergo a 90 degrees alteration of course before arriving to the carrier's mouth. A slight excess of pressure is created by this air speed into the expiration hose, so that the pressure near the expiration valve is slightly above the pressure of the air delivered to the diver. This can result in an air leak through the expiration valve during inhalation.

Such leaks are particularly observed with the breathing apparatuses of the "injection" type, where the pressurized air coming from the regulator arrives at the end of the inhalation hose then flows through said hose at a high speed, thus producing an excess of pressure in said hose.

The mouthpiece of this invention is an improvement on U.S. Patent number 2,875,756 assigned to the same assignee.

The mouthpiece according to the invention allows to eliminate the above mentioned disadvantages as well as air leaks through the expiration valve during inhalation, while giving to the apparatus carrier an improved ease of breathing. It is characterized in that a deflector is fitted on to the mouthpiece wall, facing the short conduit to the mouth, to deviate the inhaled air flow over to said mouth conduit.

This deflector can have varied shapes. It can be a bent baffle-plate fitted tangentially or nearly tangentially to the inside wall of mouthpiece and whose free end is close to the end of the mouth conduit, or else a straight baffle-plate, fitted to said wall in front of the mouth conduit. The end of said baffle-plate is preferably at right angles to the cross-section of the mouth conduit, but it can also be oblique over said cross-section.

Some examples of varied mouthpieces according to the invention and illustrated in the accompanying drawing are given hereunder, being understood that the invention may be embodied otherwise than as specifically described.

FIG. 1 illustrates the mouthpiece of this invention in relation to associated equipment in a breathing apparatus.

FIG. 2 is a section of mouthpiece provided with a deflector whose end is at right angles to the mouth conduit.

FIG. 3 is a section of mouthpiece provided with a transversal baffle-plate in front of the mouth conduit.

FIG. 4 is a section of mouthpiece provided with a deflector whose sides make some angle with the center-line of the mouth conduit.

FIG. 1 diagrammatically represents in section a portion of a breathing apparatus which portion comprises a mouthpiece 1, 2 which is provided for purposes of illustration with a deflector 6 more particularly described and illustrated with respect to FIGS. 2 to 4 inclusive. The

2

branches of the mouthpiece 1, 2 are connected by expiration hose 5 to an air regulator 20 which in turn is connected by a tube 22 to a primary air regulator or a pressurized air tank, not shown, an inhalation hose 4 joins the other branch of the mouthpiece 1, 2 to regulator 20. The expiration valve 26 located in close proximity to the diaphragm of regulator 20 functions as is described in U.S. Patent Number 2,875,756.

The mouthpiece of this invention illustrated in FIGS. 2 to 4 inclusive comprises a cylindrical casing 1, laterally connected to the mouth conduit 2 provided with rubber parts 3 to facilitate its holding by the user's teeth. This mouthpiece is connected to the demand regulator through a rubber inhalation hose, whose end 4 is shown on the figures of the drawing, and to the expiration valve through a rubber flexible expiration hose. A deflector 6 such as a bent baffle-plate fitted tangentially to the inside wall of said cylindrical casing or a straight thin-walled baffle-plate or a wedge type deflector, directs the flow of inhaled air to the user's mouth, as shown by the continuous line arrow. This deflector may possibly be supported by an inner sleeve 7, as shown in FIG. 3. The breathed out air flows to the expiration hose as shown by the dotted line arrow. Said deflector may also not occupy the whole cross-section area of casing 1; as shown in FIG. 4, some distance can be provided between the end of the deflector and the end of the mouth conduit, so long as this distance is small enough not to impair the deflection of the air flow.

What we claim is:

1. In a breathing apparatus of the open cycle type comprising a mouthpiece means connected by an inhalation air hose to a demand air regulator particularly of the injection type and connected by an expiration air hose to an exhaust valve, the improvement comprising said mouthpiece means being integrally formed as a T-pipe junction forming inhalation and expiration conduits, said inhalation and expiration conduits being aligned and connected to form opposed branches of said T-pipe junction means, the third branch of said T-pipe junction forming a common mouthpiece conduit of said T-pipe junction, and a deflector means being positioned transversely of substantially the whole cross-section of the conduit and extending between said inhalation and expiration conduits to direct air flow from the inhalation conduit toward the mouthpiece conduit and permit the escape of air from said mouthpiece conduit to said expiration conduit.
2. In a breathing apparatus according to claim 1, where-
50 in the deflector is a bent baffle-plate fitted tangentially upon the inside wall of the opposed branches of the T-pipe junction.
3. In a breathing apparatus according to claim 1, where-
55 in the deflector is a straight baffle perpendicular to the inside wall of the opposed branches of the T-pipe junction.
4. In a breathing apparatus according to claim 1, where-
60 in the end of the deflector is approximately perpendicular to the cross-section of the mouthpiece conduit.
